(57) **CLAIM**

The ornamental design for a visor, as shown and described.

DESCRIPTION

FIG. 1 is a top perspective view of a visor, showing a first embodiment of my new design;

FIG. 2 is a bottom perspective view of FIG. 1;

FIG. 3 is a front elevational view of FIG. 1;

FIG. 4 is a rear elevational view of FIG. 1;

FIG. 5 is a right-side elevational view of FIG. 1, the left-side elevational view being a mirror image thereof;

FIG. 6 is a top plan view of FIG. 1;

FIG. 7 is a bottom plan view of FIG. 1;

FIG. 8 is a top perspective view of a second embodiment thereof;

FIG. 9 is a bottom perspective view of FIG. 8;

FIG. 10 is a front elevational view of FIG. 8;

FIG. 11 is a rear elevational view of FIG. 8;

FIG. 12 is a right-side elevational view of FIG. 8, the left-side elevational view being a mirror image thereof;

FIG. 13 is a top plan view of FIG. 8; and,

FIG. 14 is a bottom plan view of FIG. 8.

The broken lines depicting stars in FIGS. 1, 3, 5, 6, 8, 10, 12, and 13 depict portions of the visor that form no part of the claimed design. The remaining broken lines represent stitching, and are part of the claimed design.

1 Claim, 12 Drawing Sheets
